UNITED STATES PATENT OFFICE.

HIRAM E. CHUTE, OF LOS ANGELES, CALIFORNIA.

BRIDLE FOR PIANO ACTIONS.

Application filed August 24, 1925. Serial No. 52,237.

This invention relates to bridles for piano actions. In the manufacture of pianos, it is common to provide the hammer butt with a bridle strap generally formed of flat webbing having one end secured in the catcher shank opening of said butt, and the other end threaded through the guide opening of the catcher and engaged with the bridle wire. In practice, this bridle is secured in the catcher shank opening by wedging it between the walls thereof and the catcher shank and by cementing these parts together, and incident thereto, should the bridle become broken when the action is used, it is very difficult and inconvenient to make repair thereof.

It is accordingly an essential object of my invention to provide a bridle which is extremely simple of construction, strong and durable, and of such character and design that will permit one to substitute it for the ordinary bridle when the latter is broken, with ease, convenience, dispatch and accuracy.

A further object of the invention is to provide a bridle constructed of a single length of material which can be looped about the catcher and passed through the guide opening thereof and firmly fastened in a novel manner to the bridle wire.

Another object of the invention is to provide a new and novel form of bridle wire engaging tip for the bridle which will be exceedingly strong and which will not accidentally pull away or break apart from the bridle wire.

Other objects and advantages of the invention will be apparent from a consideration of the more detailed description which follows.

In the accompanying drawings, which show a preferred embodiment of my invention,

Figure 1 is a view in side elevation of a part of a piano action showing an application of my improved bridle thereto;

Figure 2 is a section through the catcher on the line 2-2 of Figure 1;

Figure 3 is a plan view of the bridle; and

Figure 4 is a section through the tip on the line 4-4 of Figure 3.

On reference to Figure 1 of the drawing, I shall refer only to those parts of the action as are necessary to illustrate the use of my invention, namely, 5 the hammer butt; 6 the catcher with the usual bridle strap guide

opening 7; 8 the whippen; 9 the back check, and 10 the usual well known bridle wire.

My improved form of bridle consists of a single piece of flexible material such as 60 linen or the like, whose strands are twisted together in the customary manner of manufacturing cord. I fold or turn the cord on itself to form two long leads or branches 11-11 connected by a return bend or bight 65 12. The free ends of these branches are firmly cemented between two pieces 13-13 of a strong flexible material and the parts cemented and pressed together. The ends of the branches are relatively diverging 70 when disposed between the materials 13-13 which effects better anchorage of these parts to the end that they will not accidentally separate from one another when pull is applied thereto. Near the free end of the tip 75 formed in this manner is a perforation 14.

When the normal original or ordinary bridle strap becomes broken, I clip same near its joinder with the hammer butt, unless it so happens that this is its point of 80 severance from the action, and I then pass the bight 12 of my bridle through the guide opening 7 of the catcher 6 until the tip 13 extends into the opening, and I then pass the bight up and over the free end of the tip, 85 after which the tip is pulled forward until the branches 11 are drawn taut. By this arrangement, separate loops 15 are formed which embrace the sides of the shank 6^a of the catcher, as is clearly shown in Figure 2. 90 The tip is then secured to the bridle wire 10 by passing the pointed end of the latter through the opening 14 of the tip. It will be noted that the loops 15 are arranged above the branches 11-11, so as to prevent displacement of the bridle from the catcher. 95

In the manner aforesaid, the bridle can be made to quickly replace a broken bridle strap of the usual form, and by forming my bridle with the relatively spaced loops 100 15-15 the strain applied to the bridle is equalized and the bridle cannot be easily torn away from its mounting. Also from the manner of forming my improved tip, a very serviceable connection thereof may be 105 made at the bridle wire 10 so that it cannot accidentally tear away therefrom.

I claim:

1. As a new article of manufacture, a bridle for piano actions formed of a single 110 length of cord looped upon itself, and a flexible tip comprising two sheets of material

secured to each other and between which the free ends of the cord are secured.

2. As a new article of manufacture, a bridle for piano actions formed of a single length of cord looped upon itself, and a flexible tip comprising two sheets of material secured to each other and between

which the free ends of the cord are secured in diverging relation to each other and in converging relation to one end of the tip, the sheets of the tip being tapered toward said ends. ¹⁰
